WAX APPLIER

Warren G. Bailey, Evanston, Ill., assignor, by
mesne assignments, to Reconstruction Finance
Corporation, Chicago, Ill., a corporation

Application September 13, 1937, Serial No. 163,669

1 Claim. (Cl. 15—231)

This invention relates to a wax applicator. It will be obvious, however, that the invention is applicable to other uses.

An object of the invention is to provide a simple structure which will apply wax, and particularly liquid wax of the non-rubbing type, to surfaces while at the same time providing a structure which can be readily cleaned and dried. A further object is to provide mechanism for supporting wax-applying fabric in such a manner as to permit the fabric to be readily removed and cleaned, and also to permit the ready drying of the material after reassembling. A further object is to provide a wax-applying flexible member which is stretchable so as to maintain itself in taut position while at the same time preventing the escape of wax through the fabric. Other specific objects and advantages will appear as the specification proceeds.

20 The invention is illustrated in a preferred embodiment by the accompanying drawing, in which—

Figure 1 is a plan view of a wax-applicator embodying my invention, a portion of the handle having been cut off; Fig. 2, a transverse sectional view, the section being taken as indicated at line 2 of Fig. 1; Fig. 2, a broken transverse sectional view, the section being taken as indicated at line 3 of Fig. 2; and Fig. 4, an enlarged broken sectional view of the rubber reinforced fabric employed.

In the illustration given, A designates a handle; B, a frame secured to the handle; and C, a wax-applying fabric.

35 The handle A may be of any suitable construction and material. In the illustration given, a wooden handle is shown provided near its lower end with an opening 10 through which a bolt 11 is passed for securing it to frame B.

40 The frame B may also be of any suitable construction or material. In the illustration given, the frame B consists of two members. The lower metal member 12 provides a rounded lower surface and upwardly extending spring locking arms 13. The upper metal member 14 is equipped at its sides with a U-shaped channeled edge 15 which serves to clamp the edges of the fabric member C against the spring arms 13 of member 12.

45 The upper member 14 provides with the lower member 12 open ends through which air may circulate freely through the chamber between the members. To provide further ventilation for drying purposes, I prefer to partially cut away portions of the plate 14 near its center and

5 to form from these partially cutaway portions upwardly extending handle-engaging flanges 16. The flanges 16 are provided with an opening coinciding with the opening 10 which extends through handle A and the bolt 11 passes through this opening and opening 10 to secure handle A rigidly to the flanges 16, as shown more clearly in Figs. 1 and 3. The striking out of the metal leaves apertures 17 near the center of the plate 14.

10 The wax-applying member C may be of any suitable construction and material. In the illustration given, I provide a rubber backing or base 18 and a mohair or brush-like fabric body 19. The brush-like threads of the mohair are reinforced near their rear side with an undulating fabric mat 20, as shown more clearly in Fig. 4, thus permitting stretching of the member C. In this construction, the rubber base provides an impervious backing which prevents the liquid 20 from passing through the member C while also reinforcing the brush-like fabric or mohair body. The result is a tough strong applying structure which is impervious and which at the same time is stretchable. When applied to the frame, as 25 shown in Fig. 3, the member C is stretched and held taut in the position shown, the brush-like fibers of the cloth being supported in even regular position.

30 In the application of the liquid, the brush-like fibers retain between them a quantity of the liquid and cause it to spread evenly and uniformly over the desired surface, the individual fibers tending to move into any uneven interstices or depressions in the surface to be waxed 35 and applying the liquid solution there.

After the waxing operation, the plate 14 can be slid readily out of engagement with the member 12 so as to free the applying member C. Member C can then be washed and the parts reassembled. In reassembling, the fabric C is applied around the lower member and then the plate 14 is pressed downwardly, spreading spring arms 13 until the channeled edge 15 is in the position shown in Figs. 2 and 3, in which position 45 the member C is locked in a stretched condition resulting from this described operation. In this position, the applicator can be set aside to dry, the air circulating freely through the ends of the chamber formed between the members and 50 through apertures 17 in the middle portion thereof.

The wax applicator is of extremely simple construction, can be operated efficiently for spreading the liquid evenly upon the surface, and can 55

be readily disassembled and assembled after cleaning, the structure being such as to maintain the fabric in taut condition with the brush-like fibers maintained in substantially vertical position.

The foregoing detailed description has been given for clearness of understanding only, and no unnecessary limitations should be understood therefrom, but the appended claim should be construed as broadly as permissible, in view of the prior art.

I claim:

In a wax applicer, a frame provided with two

superposed members, said superposed members having side flanges, the side flanges of said superposed members being in releasably interlocking relation, a wax-applying flexible and stretchable member extending under the lowermost of said members and having portions thereof clamped between said side flanges whereby said member is stretched and held taut, said flexible member consisting of an elastic inner base layer and an outer fabric layer, said layers being joined with the fabric undulated. 5 10

WARREN G. BAILEY.
